US00D572868S

(12) **United States Design Patent**
McKay

(10) **Patent No.:** **US D572,868 S**
(45) **Date of Patent:** **** Jul. 8, 2008**

(54) **GROOMING TOOL**

(75) Inventor: **William D. McKay**, Grand Blanc, MI
(US)

(73) Assignee: **The Hartz Mountain Corporation**,
Secaucus, NJ (US)

(**) Term: **14 Years**

(21) Appl. No.: **29/243,159**

(22) Filed: **Nov. 18, 2005**

(51) LOC (8) Cl. **30-99**

(52) U.S. Cl. **D30/158**

(58) Field of Classification Search 15/104.002,
15/230.11, 104.94, 104.8, 23, 231, 169, 184,
15/114, DIG. 14, 186-188; D30/158, 159;
